Victor J. Evans
ATTORNEY

UNITED STATES PATENT OFFICE.

JOSEPH F. BUSHEE, OF JERSEY CITY, NEW JERSEY.

SMOKING PIPE.

Application filed April 6, 1925. Serial No. 21,109.

This invention relates to smoking pipes and is an improvement over the pipe shown in my co-pending application filed February 18th, 1925, Serial No. 10,127.

- 5 The principal object of the invention resides in a smoking pipe wherein the nicotine and moisture is absorbed and the smoke cooled prior to its passage from the bowl to the stem, in order that a dry and cool 10 "smoke" may be had by a person during the smoking of a charge of tobacco contained in the bowl, thus assuring a more enjoyable "smoke" as the same will not "bite the tongue".
- 15 Another object of the invention is to provide a smoking pipe which includes a means for filtering the smoke and for cooling the same, and whereby the same may be easily taken apart for cleaning purposes.
- 20 A further object of the invention is to provide a smoking pipe which is simple in construction, cheap of manufacture and novel of design.

With these and other objects in view, the 25 invention resides in certain novel construction and combination and arrangement of parts, the essential features of which are hereinafter fully described, are particularly pointed out in the appended claims, and are 30 illustrated in the accompanying drawing, in which:—

Figure 1 is a side elevation of my improved smoking pipe.

Figure 2 is a vertical longitudinal sectional view therethrough.

Figure 3 is a vertical transverse sectional view on the line 3—3 of Figure 2.

Figure 4 is a detail sectional view of a modified form of my invention.

40 Referring more particularly to the drawing, the reference numeral 10 designates my improved smoking pipe in its entirety, and which includes a bowl 11 having a stem 12 extending from one side thereof and a projecting boss 13, extending from the opposite side, and which boss is externally screw-threaded as at 14, and is provided with a concaved recess 15. The bore 16 of the stem opens into the recess and receives one end 45 of a tube 17 formed of aluminum or the like. A passage 18 also communicates with the recess 15 above the bore 16, and leads to the bottom of the interior of the bowl 11. A tube similar to the tube 17 may be 50 inserted in the passage 18 or the same may be omitted.

A disk or plate 19 closes the recess 15 and is pivoted to the boss as at 20 in order to permit the plate to be swung to a position to uncover the recess for a purpose to be explained. The plate 19 is formed with a pair of openings 21 and 22, and the tube 17 extends through the opening 22, while the opening 21 establishes communication between the recess and a cooling chamber 65 23 formed in a cap 24 which has connection with the threads 14 on the boss. The free end of the tube 17 terminates within a chamber and it will be seen that in operation, a suction set up at the mouth piece of 70 the stem will cause smoke from the bowl to pass through the passage 18 into the recess 15, then through the opening 21 into the chamber 23, through the tube 17 and thence through the bore 16 of the stem.

75 The recess 15 and the plate 19 house a sponge or other absorbent member 25 which filters the smoke in its passage from the bowl to the chamber. Any moisture and nicotine which the smoke may contain will 80 be absorbed by the sponge before it reaches the chamber where the dry smoke is cooled by the atmospheric air acting against the walls of the cap 24. It will be seen that by the time it reaches the bore in the stem, the 85 same has been removed of all impurities and has been reduced to a comparatively cool state. By this arrangement the bore in the stem is always kept clean and the user assured of a dry and cool smoke.

90 As the sponge 25 becomes filled with moisture, the cap 24 may be readily removed and the tube 17 withdrawn, the plate 19 turned about its pivot to uncover the recess, at which time the sponge may be removed 95 and the moisture squeezed therefrom, or a fresh absorbent substituted therefor.

I wish it to be understood that the cap 24 may be of any shape, and of any suitable material such as metal or wood, without in 100 any way departing from the spirit of my invention, and that I may make such changes in construction as come within the scope of the appended claims.

In Figure 4 of the drawing, I have shown 105 a slightly modified form of my invention wherein the parts are reversed but the result is approximately the same as that of the preferred form. In this form a tube 18' leads from the bowl to the chamber 23', 110 while the bore 16 of the stem enters the recess 15. The plate 19' is removably seated

to close the recess and has an opening 26 therein of a size larger than the tube 18' and through which the tube extends. The absorbent member 25 instead of being positioned in the recess, is housed in the chamber 23', and in which chamber the moisture is collected. In use, the smoke passes from the bowl through the tube 18' into the chamber 23', then through the open space about 10 the tube 18' into the recess, and then through the bore in the stem. By this arrangement the absorbent member may be quickly removed for cleaning purposes by removing the cap 24.

15 What is claimed as new is:—

1. A smoking pipe comprising a bowl, a stem extending therefrom having a bore therethrough which opens at the front of said bowl, a pocket formed on one side of 20 said bowl, a passage leading from the interior of the bowl to said pocket, an absorbent member, means for removably securing said absorbent member within said pocket, a removable cap enclosing said means 25 and co-acting therewith to form an enlarged chamber for communication with said bore.
2. A smoking pipe comprising a bowl, a boss formed thereon having a recess therein adapted to house an absorbent member, a 30 passage leading from the interior of said bowl to said recess, a closure member for said recess and having an opening therein, a cap removably associated with said boss and co-acting with said closure member to 35 provide a chamber, and a stem extending from said bowl and having a bore therein opening at the free end thereof and communicating with said chamber.

3. A smoking pipe comprising a bowl, a recess formed thereon, a passage connecting 40 said recess with the interior of said bowl, a swinging closure member for housing an absorbent member within said recess, said closure member having an opening therein, a cap removably attached to said bowl and co-acting 45 with said closure member to define an enlarged chamber, a stem extending from said bowl, and a duct for establishing communication between said chamber and the free end of said stem. 50

4. A smoking pipe comprising a bowl, a stem extending therefrom and having a bore therethrough which opens at the front of 55 said bowl, a pocket formed at the end of said bowl, a passage leading from the interior of said bowl to said pocket, a closure plate for said pocket having an opening therein, and a cap enclosing said closure plate and co-acting therewith to provide an enlarged chamber for communication with 60 said bore.

5. A smoking pipe comprising a bowl, a pair of communicating chambers, a stem extending from said bowl and having a bore therethrough which communicates with one 65 of said chambers, a passage connecting the interior of said bowl with the other of said chambers, whereby the smoke in its passage from said bowl during the smoking of a charge of tobacco therein will pass in a direction away from the mouth piece of said 70 stem and thence through said chambers and said bore to the mouth piece.

In testimony whereof I have affixed my signature.

JOSEPH F. BUSHEE.
